UNITED STATES PATENT OFFICE

CLAUDE W. METZGER, OF HOUSTON, TEXAS

DRILLING TOOL

Application filed July 9, 1928. Serial No. 291,227.

This invention relates to new and useful improvements in a drilling tool.

One object of the invention resides in the provision of a drilling tool of the character described adapted to be attached to the lower end of a drill stem and embodying a head, and a plurality of blades secured in the head, and removable therefrom, to the end that any or all of the blades may be removed and 10 replaced in case they become worn with use or broken.

Another object of the invention is to provide a drilling tool of the character described embodying a pilot blade of the fish tail bit type and side blades associated with the pilot blade and whose cutting edges project out 15 beyond the head to enlarge the bore to provide clearance for the head, said tool also having radially extending reaming blades, 20 all of said blades being detachably secured in the head in such manner that a bridgelike structure will be provided to the end that each blade will be supported against endwise thrust inwardly by such bridgelike supporting structure and such endwise thrust imparted to any blade will be distributed to 25 and sustained by the other blades.

A further feature of the invention resides in a novel structure for securing the blades in the head of such construction that in case of 30 wear permitting movement of the blades relative to the head that each blade may move on its own axis in the head thus preventing the driving strain on any blade from being concentrated at any point of the blade, and lessening the liability of the blades from becoming broken as more particularly described hereinafter.

A still further feature of the invention resides in the provision of novel means for 40 supplying flushing fluid to the drilling blades at the lower end of the head.

With the above and other objects in view the invention has particular relation to certain novel features of construction, operation 45

and arrangement of parts an example of which is given in this specification, and illustrated in the accompanying drawings wherein:—

Figure 1 shows a vertical sectional view of 50 the drilling tool.

Figure 2 shows a vertical sectional view thereof taken at right angles to the view shown in Figure 1.

Figure 3 shows a lower end view of the tool, 55 and

Figure 4 shows a cross sectional view taken on the line 4—4 of Figure 1.

Referring now more particularly to the drawings, wherein like numerals of reference 60 designate similar parts in each of the figures, the numeral 1 designates a tubular head whose upper end is provided with a tapering internally threaded socket 2, adapted to receive the externally threaded tapering pin 3, of the 65 drill collar 4 through which the drilling tool may be connected to the drill stem. This collar has an axial water channel 5 therethrough. The lower end of the head has an inwardly extending flange 6 which has the transverse 70 blade slots 7 and 8 cut therethrough and disposed at substantially right angles to each other, said slot 7 extending entirely across the head. Side boring blades 9, 9 are provided. These blades 9 are fitted through the 75 slot 7 and are thus oppositely disposed and spaced apart. They have the upwardly extended shanks 10, 10, and are widened each way and thus rest on the flange 6. The outer sides of the shanks are convex and abut 80 against and conform to the contour of the inside of the head 1.

The inner sides of the shanks 10 converge downwardly and are concave forming the seats 11. The cutting edges of the blades 9 85 extend out the required distance beyond the head so as to form a bore of sufficient diameter to clear the head as the tool moves downwardly in drilling.

The numeral 12 designates a pilot blade 90

- preferably of the fish tail type, which is fitted through the slot 8 and which preferably extends beneath the lower cutting edges of the blades 9. The upper end of this pilot blade 12 is formed with an inverted frusto-conical shaped anchor block 13 which fits closely in the seats 11 of the shanks 10. The upper face of this block has a downwardly tapering socket 14 therein, in which is seated the downwardly tapering stud of the frusto-conical shaped wedge block 16 which rests upon the anchor 13.
- The head 1 has the oppositely disposed radial slots 17, 17 through which the reaming blades 18, 18, are fitted. The inner ends of the reaming blades 18 have the arcuate widened shanks 19, 19 whose outer faces conform to the contour of and fit against the opposing inner wall of the head 1. The upper inner corners of the shanks 19 are downwardly tapered and concaved forming the seats 20, 20 and a ring nut 21, is threaded through the internally threaded contracted portion 22 of the head 1. The lower end of this ring nut is downwardly tapered and blank, as at 23, and when screwed home, seats firmly in the seats 22, with wedge like effect and anchors the reaming blades 18, firmly in place, and holds them securely against the upper end of the anchor 13.
- An outwardly threaded sleeve 24 is threaded through the nut 21. Formed integrally with said sleeve 24, and depending therefrom are the arms 25 whose lower ends are formed with the arcuate wickers 26. When the sleeve 24 is screwed home the wickers 26 wedge between the expander 16 and the opposing insides of the shanks 19, the inner sides of said wickers being outwardly flared to conform to the contour of and fit closely against the upwardly tapering external face of the expander 16. The sleeve 24 serves also as a locking means for preventing the unscrewing of the nut 21.
- Any end thrust imparted inwardly to either reaming blade 18 will be transmitted through this anchoring structure to the other reaming blade as well as to the anchor block 13 and any upward thrust imparted to either of the blades 9 or 12 will be sustained by the bridgelike anchoring structure described.
- Should either of the slots through which the blades work become worn so as to permit movement of the blade relative to the head 55 while drilling, the entire blade will be permitted to slightly pivot or turn on an axis by reason of the circular or arcuate seats of said blade against its anchoring structure. This construction permitting movement of the entire blade will prevent the concentration of the stress at any particular point and this will lessen the likelihood of the blade breaking under the stress of the work to which it is subjected. The flange 6 has the oppositely disposed outwardly inclined water channels 27, 27 leading therethrough and directed toward the front faces of the blades 9, so as to discharge the flushing fluid near the cutting edges of said blades; and said flange also has the oppositely disposed inwardly inclined water channels 28, 28 directed toward the forward faces of the cutting edges of the blade 12.
- The flushing fluid passes from the stem through the channel 5 and the sleeve and out through the opening 29 between the arms 25 into the enlarged chamber 30 of the head 1, and thence downwardly through the channels 27, 28 to flush the boring blades 9 and 12.
- While I have shown what I now consider to be the preferred form of the invention it is obvious that mechanical changes may be made therein and equivalents substituted for the parts shown, and I reserve the right to make such mechanical changes and substitutions as may be comprehended within the principle of the invention.
- What I claim is:—
1. A drilling tool embodying a tubular head having vertical and lateral blade bearings, blades fitted through said bearings, abutments carried by the blades which abut the inner side of the head, removable, expandable, tubular means screwed into the head and abutting the inner ends of the blades, and clamping said abutments firmly against the head. 90
  2. A drilling tool including a tubular head having lower end slots and side slots, oppositely disposed side boring blades, and a pilot blade fitted through said end bearings, widened shanks carried by said side blades and abutting the adjacent sides and lower end of the head, said shanks being formed with inside seats, an anchor carried by the upper end of the pilot blade and seated in said seat, reaming blades fitted through said side slots and having their inner ends widened and resting on said anchor and against the adjacent parts of the head and removable means secured in the head and abutting the inner ends of said reaming blades. 100
  3. A drilling tool including a tubular head having lower end bearings and side bearings, oppositely disposed side boring blades, and a pilot blade fitting through said end bearings, widened shanks carried by said side blades and abutting the adjacent sides and lower end of the head, said shanks being formed with inside seats, an anchor carried by the upper end of the pilot blade and seated in said seat, reaming blades fitted through said side bearings and having their inner ends widened and resting on said anchor and against the adjacent parts of the head and removable means secured in the head and abutting the inner ends of said reaming blades. 110
- 120
- 125
- 130

and a sleeve threaded into said nut and having expandible wickers which wedge against the inner ends of the reaming blades.

4. A drilling tool including a tubular head having lower end slots and side slots, oppositely disposed side boring blades, and a pilot blade fitted through said end slots, widened shanks carried by said side blades and abutting the adjacent sides and lower end of the head, said shanks being formed with inside seats, an anchor carried by the upper end of the pilot blade and seated in said seat, reaming blades fitted through said side slots and having their inner ends widened and resting on said anchor and against the adjacent parts of the head and removable means secured in the head and abutting the inner ends of said reaming blades, said removable means comprising an expander or said anchor, a ring nut threaded into the head and abutting the inner ends of the reaming blades, a sleeve threaded into said nut, expandible means carried by said sleeve and wedged between said expander and the opposing ends of said reaming blades.

5. A drilling tool including a tubular head having blade bearings, blades fitted through said bearings and having cutting edges which project out beyond the head, anchoring means secured within the head and removable therefrom and comprising an expander and expandible wedges, the inner ends of the blades being enlarged and clamped between said anchoring means and the head.

6. A drilling tool including a tubular head having blade bearings, blades fitted through said bearings and having cutting edges which project out beyond the head, anchoring means secured within the head and removable therefrom, the inner ends of the blades being enlarged and clamped between said anchoring means and the head, said anchoring means comprising expandible means and an expander, said tool having a fluid passageway downwardly therethrough which terminates in discharge channels directed against the forward sides of the blades at the lower end of the head.

7. A drilling tool including a tubular head having side bearings, reaming blades fitted through said bearings, means on the inner ends of the reaming blades abutting the head, removable means in the head abutting the inner ends of the reaming blades, an expander in the head, having a tapering surface and expandible means in the head wedged between said expander and the inner ends of said reaming blades.

8. A drilling tool including a tubular head having side bearings, reaming blades fitted through said bearings, means on the inner ends of the reaming blades abutting the head to hold said blades against outward movement, removable means in the head abutting the inner ends of the reaming blades and

holding said blades against inward movement, an expander in the head, expandible means in the head wedged between said expander and the inner ends of said reaming blades, said expandible means and securing said blades in place, the lower end of the head having bearings, a pilot boring blade and side boring blades fitted through said end bearings, means carried by the inner ends of said side boring blades and clamped between the expander and head and interlocking said boring blades with the head and having inside seats, an anchor carried by the upper end of said pilot blade and seated in said seat and abutting the inner ends of the reaming blades and supporting said reaming blades and expander.

9. A drilling tool including a tubular head having lower end blade bearings and side blade bearings, a pilot blade and side boring blades fitted through said end bearings, means carried by the inner ends of the side boring blades which abut the head and hold said side boring blades against outward movement, said blade holding means being formed with inside seats, an anchor attached to the pilot blade and seated in said seats to support said pilot blade, reaming blades fitted through said side bearings, means carried by the inner ends of the reaming blades and abutting the head to secure said reaming blades therein, said blade securing means being formed with inside seats and removable means in the head abutting the seats of inner ends of the reaming blades and also abutting said pilot blade anchor to lock said reaming blades and anchor in the head.

10. A drilling tool including a tubular head having lower end blade bearings and side blade bearings, a pilot blade and side boring blades fitted through said end bearings, means carried by the inner ends of the side boring blades which abut the head to lock said side boring blades against outward movement, said locking means being formed with inside seats, an anchor attached to the pilot blade and seated in said seats, reaming blades fitted through said side bearings, means carried by the inner ends of the reaming blades and abutting the head to lock said reaming blades against outward movement, said locking means for said reaming blades being formed with inside seats and removable means in the head abutting the seats of the inner ends of the reaming blades and also abutting said pilot blade anchor, said removable means comprising an expander on said anchor, a wedging device anchored in the head and having a tapering face seated against the seats of said reaming blades and also having expandible means wedged between said expander and the inner ends of the reaming blades.

11. A drill including a hollow tubular head having blade slots, blades having enlarged

inner ends, said blades being fitted through said slots with their enlarged ends abutting the inner side of the head, and means removably secured in the head and abutting said inner ends of said blades and securing said blades in the head, said means comprising an expander and wedging means cooperating with said expander.

12. A drill including a hollow tubular head having blade slots, blades having enlarged inner ends, said blades being fitted through said slots with their enlarged ends abutting the inner side of the head, tubular means removably secured in the head and having wedges which abut some of said inner ends of said blades, an expander effective to expand said wedges into said abutting relation and effective to also abut other of said blades.

13. A drill having a hollow head having side slots for reaming blades and lower end slots for pilot boring blades and side boring blades, blades shaped to fit snugly through said slots and having enlarged inner ends which engage the head, an anchor in the head engaging said enlarged ends of some of said boring blades, an expander in the head engaging the said ends of other of said boring blades, and means detachably secured in the head which wedge between the expander and said ends of the remaining blades.

In testimony whereof I have signed my name to this specification.

CLAUDE W. METZGER.
